UNITED STATES PATENT OFFICE.

SANUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed January 16, 1920. Serial No. 351,865.

To all whom it may concern:

Be it known that I, SAMUEL B. WILLIAMS, Jr., a citizen of the United States, residing at Brooklyn, in the county of Kings, State of New York, have invented certain new and useful Improvements in Telephone Systems, of which the following is a full, clear, concise, and exact description.

This invention relates to telephone systems and more particularly to automatic switches for interconnecting lines in such systems.

It is the object of this invention to provide a switch of simple structure and positive operation which may be moved in a single direction to connect one telephone line with either a particular line or with an idle one of a group of lines.

Referring to the drawings, Figs. 1, 2 and 3 with Fig. 1 to the right of Figs. 2 and 3 show a telephone system embodying the present invention. Fig. 1 shows a perspective view of a switch embodying this invention together with a diagram of circuits for controlling the switch, and a subscriber's substitution; Fig. 2 shows an incoming trunk line with one end of a cord circuit for connection therewith; and Fig. 3 shows an outgoing trunk line with one end of the cord circuit for connection therewith. The equipment shown to the right of the dotted lines in Figs. 2 and 3 is preferably located in the same office as that shown in Fig. 1, and that shown to the left of the dotted lines 35 may be located at a central office.

In the present embodiment of the invention, a switch such as is disclosed in Fig. 1 is provided individual to each subscriber's line as well as each incoming trunk line. The switch comprises frame pieces 1 and 2, the ends of which are slotted to receive a bar 3 slidable therein. A rod 4 secured to the frame in any suitable manner rotatably supports a number of contact operating arms 5, which are provided at one end with ears 6 to receive the rod 4, and at the other end with pins 7 carrying rollers 8. Secured to the rod 4 are coil springs 9 which keep the rollers 8 in contact with the upper surface of the bar 3. An arm 5 is provided for each subscriber's line, and for each outgoing trunk line to which the switch has access in addition to which there are provided two arms 5 shown at the right of Fig. 1 for a purpose to be later described.

Secured in any suitable manner to the bottom of each arm 5, which is individual to an outgoing trunk line, is a block of insulating material 10 in which are held springs 11, 12, 13 and 14, the rear ends of which are adapted to be used for soldering terminals. The front ends of these springs are adjusted to normally rest above line bars 15, 16, 17, and 18 which are rigidly secured to the frame and insulated therefrom in any suitable manner. Similarly each arm 5 individual to a line within the local office carries springs 12, 13 and 14 which cooperate with bars 16, 17 and 18 respectively.

The bar 3 is provided with notches 19 and a cam surface 20 which are spaced so that movement of the bar 3 to the right from normal position will allow rollers 8 to successively ride into the notches 19, thereby bringing springs 11, 12, 13 and 14 into engagement with bars 15, 16, 17 and 18 respectively. The distance between successive notches 19 is consequently made greater than the distance between successive arms 5 by an amount equal to the length of one or more teeth of the ratchet 21. Secured to the frame member 2 is a stepping magnet 28 carrying an armature lever 24 at one end of which is pivotally mounted a pawl 25. The pawl 25 is held in engagement with a pin 26, fixed to the frame, by a spring 27 and is arranged so that when the armature 24 is in normal position, the pawl 25 is clear of bar 3. When armature 24 is attracted, pawl 25 engages one of the teeth 21 which are cut on the lower side of bar 3 and moves the bar 3 to the right. Secured to frame 1 by a screw 28 is a resetting or releasing magnet 29 provided with an armature 30 pivoted to one end of which is a pawl 31. Pawl 31 is held in engagement with a pin 32, which is secured to the frame, by a spring 33 so that when armature 30 is retracted, pawl 31 is clear of the teeth 22 cut in the lower surface of bar 3. When armature 30 is attracted, however, pawl 31 rides into engagement with teeth 22 and moves the bar 3 to the left. Two pairs of normally closed contact springs 34, 36 and 35, 37 are mounted on the frame in any suitable manner, and are controlled by armatures 24 and 30 respectively to open their contacts near the end of the attractive step of these armatures. Carried on the arm 5, shown to the right in Fig. 1 and designated 110

as TK, is a rod 38 of insulating material which supports one end of springs 39, 40, 41 and 42. The other end of these springs is supported in a block of insulating material 43 which is fixed to the frame in any desired manner. Block 43 also carries springs 44, 45, 46, 47, 48 and 49, which cooperate with the springs carried by the rod 38. When bar 3 is in normal position, the following pairs of contact springs are closed 39, 45, 40, 47 and when the bar 3 has been moved to the right far enough to cause the roller of the arm TK to ride up on cam surface 20, these springs are opened and springs 39, 44, 40, 46, 41, 48, and 42, 49 will be closed.

Upon similar manner, arm ON controls springs 50, 51, 52, 53, 54, 55, 56, 57 and 58 so as to normally close the following pairs of springs 50, 51, 53, 54, 55, 56, and to open these contacts when bar 3 is in any position other than normal, thereby closing the following pairs of springs 52, 53 and 57, 58.

The conductors T, R and S of each subscriber's line are multiply connected to a set of springs 12, 13 and 14 carried by an arm 5 in each switch of the local office.

The functions of the switch will be more readily understood from a consideration of the operation of a system using such a switch, which is as follows:

A subscriber at "A" desiring connection with another subscriber located in the same office removes his receiver from its hook, thereby completing an energizing circuit for relay 59 which may be traced from ground, through the secondary winding of tone source 80, springs 54 and 53, impedance coil 60, back contact and inner armature of cut-off relay 61, through the apparatus at station A, outer armature and back contact of relay 61, the winding of relay 59 and the impedance coil 62 to grounded battery. In addition to energizing relay 59, this circuit transmits a tone to the subscriber to notify him that he is connected to a switch and may operate his calling device. Relay 59, in attracting its armature, completes an obvious circuit for slow release relay 63. Relay 63, in attracting its left-hand armature connects ground potential to conductor S which is multiply connected to the contact springs 12 corresponding to the calling line in each switch in the local office. The subscriber now operates his calling device 64 to interrupt the line circuit a number of times corresponding to the number of the called subscriber within the local exchange, thereby vibrating the armature of relay 59. Upon the first retraction of the armature of relay 59, a circuit is completed from ground, armature and back contact of relay 59, inner right-hand armature and front contact of relay 63, conductor 66, through the winding of the stepping magnet 23 to grounded battery. Magnet 23 and relay 65 are energized in this circuit, magnet 23 attracting its armature 24, thereby causing bar 3 to move one step to the right so that the roller 8 of the first line drops into its notch 19, and roller 8 of the off-normal arm ON is raised from its notch 19 to the upper surface of bar 3, to operate the off-normal springs 50 to 58 in the manner previously described. Spring 53 in breaking contact with spring 54 and making contact with spring 52 removes the dialing tone from the calling line and provides a substitute circuit for stepping relay 59. Upon the second and succeeding retractions of the armature of relay 59, a circuit is completed from ground, armature and back contact of relay 59, inner right-hand armature and front contact of relay 63, right-hand armature and front contact of relay 65, through the winding of relay 65, conductor 66, through the winding of the stepping magnet 23 to grounded battery, thus maintaining relay 65 energized and causing the magnet 23 to step bar 3 to the right, successively dropping each roller 8 into its notch 19 and returning it to the upper surface of bar 3 until the roller 8 of the desired line which will be assumed to be the line S. R, T, drops into its notch 19. Upon the first deenergization of line relay 59, a circuit was also completed in parallel with that traced from ground, armature and back contact of relay 59, inner right-hand armature and front contact of relay 63, right-hand armature and back contact of relay 65, through the winding of relay 67 to grounded battery. Relay 67 was energized in this circuit and locked up over a circuit extending from battery, through the winding, front contact and armature of relay 67, the armature and back contact of relay 68, and the front contact and outer right-hand armature or relay 63 to ground. If the called line is busy, ground potential will be found on its conductor S, being supplied thereto through the left-hand armature of its relay 63 if the line is busy as a calling line, and in a manner to be described if the line is busy as a called line. This ground will be extended over spring 12, bar 16, conductor 69, left-hand armature and spring 70 of relay 65, and through the winding of test relay 71 of the calling line to grounded battery. Relay 71 will be energized in this circuit and upon the deenergization of relay 65, due to the cessation of impulses from the line relay, a locking circuit will be completed for relay 71 from battery, through the winding of relay 71, spring 70 and its normal contact, front contact and right-hand armature of relay 71, conductor 72, front contact and outer right-hand armature of relay 63 to ground. A busy tone will

then be transmitted to the calling subscriber from ground, through the left-hand winding of the transformer BZ, front contact and inner left-hand armature of relay 71, back contact and inner armature of relay 61, through the apparatus at substation A, outer armature and back contact of relay 61, winding of relay 59 and impedance coil 62 to grounded battery. The calling subscriber 5 hearing this tone will replace his receiver on its hook, thereby interrupting the circuit for line relay 59. Relay 59, in deenergizing, opens the circuit for relay 63 which deenergizes to complete a circuit from ground, 10 armature and back contact of relay 59, inner right-hand armature and back contact of relay 63, springs 57 and 58 closed while the switch is away from normal position, springs 37 and 35, through the winding of 15 the release magnet 29 to grounded battery. Magnet 29 is energized in this circuit and in attracting its armature 30 forces pawl 31 into engagement with a tooth 22 to move the bar 3 to the left and opens the contact 20 between springs 35 and 37 to interrupt its own circuit, thereby causing its deenergization. Upon each retraction of armature 30, this circuit is again completed by the closure 25 of springs 35 and 37 so that magnet 29 continues to move the bar 3 until it reaches its normal position, at which time roller 8 of the arm ON in dropping into its notch 19 permanently interrupts the release magnet 30 circuit by opening the contacts between 35 springs 57 and 58. Relay 63, in retracting its outer right-hand armature, interrupted the locking circuits of relays 67 and 71 and the switch is completely restored.

If the called line is found idle, battery potential 40 will be present on its conductor S², being supplied thereto from grounded battery, through the winding of cut-off relay 61 of the called line, back contact and left-hand armature of relay 63 of the called line to its conductor S, and a circuit will be completed 45 through conductor S¹, spring 12, bar 16, conductor 69, left-hand armature and back contact of relay 65, through the left-hand winding of relay 73, back contact and right-hand armature of relay 71, conductor 72, 50 through the front contact and outer right-hand armature of relay 63 to ground. Relay 61 of the called line and relay 73 of the calling line are energized in this circuit, relay 61 cutting off the line relay of the called line. Relay 73, in attracting its inner right armatures, completes a circuit for ringing the called subscriber's bell from grounded battery, through the secondary winding of 55 transformer 74, through the winding of relay 68 of the calling line, front contact and left-hand armature of relay 67, front contact and middle right-hand armature of relay 73, 60 springs 47 and 40, bar 17, spring 13, conductor R, conductor R², conductor R of the called line, through the apparatus at the called substation, conductor T of the called line, conductor T², spring 14, bar 18, springs 39 and 45, innermost right-hand armature and front contact of relay 73, through the impedance 70 coil 60 and springs 53 and 52 to ground. A by-path circuit for ringing current is also provided through the contacts of the inner right armatures of relay 73 and the resistance 81 to the apparatus of the calling substation to provide ringing tone to notify the calling subscriber that the called station is being signalled. The resistance 81 is of such a value that the ringing current traversing the calling subscriber's circuit is sufficient to 75 be heard, but not sufficient to be annoying, nor is it sufficient to cause the energization of relay 68. Resistance 81, being of the non-inductive type, as indicated, forms a shunt around relay 59 when the talking circuit is completed so that the transmission of talking current is not affected by the inductive winding of relay 59. The bell at the called station is rung in the circuit above described but relay 68 is marginal and will not energize until the called subscriber answers. At this time, relay 68 is energized to interrupt the locking circuit previously traced for relay 67 and relay 67 in retracting its left-hand armature cuts off the ringing current. 80 The calling and called substations are now connected for conversational purposes over the circuit shown in heavy black conductors in Fig. 1, battery being supplied to both calling and called lines through impedance 100 coils 60 and 62, and relay 59 being held energized over the loop of the calling subscriber's substation. At the conclusion of the conversation, when both subscribers have replaced their receivers on their hooks, the 105 circuit for relay 59 is interrupted to deenergize this relay. Release of the connection and restoration of the switch to normal now takes place in exactly the same manner as was described when the calling subscriber 110 abandoned the connection upon finding the called line busy.

If the subscriber at station A desires a central office connection, he operates his calling device 64 to send a greater number of 115 impulses than are required to operate his switch to connect him with any other subscriber's line in the branch exchange, thus relays 59, 63, 65 and 67 are operated in the same manner as was described for a connection within the branch exchange, but the stepping magnet 28 moves bar 3 to the right until the arm TK is raised to operate springs 39 to 49 by the engagement of roller 8 with cam surface 20 of bar 3. Simultaneously, 120 with the operation of these springs, the arm 5, shown at the extreme left of Fig. 1, drops into its notch 19, thereby completing contact between springs 11, 12, 13 and 14 and bars 15, 16, 17 and 18 respectively. If this 125 130

trunk is busy, ground potential will be found on its conductor 76 being supplied thereto over a circuit which may be traced from ground through the outer right-hand armature and front contact of relay 63 of the line with which this trunk line is already occupied, conductor 72 of said line, inner left-hand armature and front contact of relay 73, back contact and left-hand armature of relay 65, conductor 69, bar 16, spring 12 and conductor 76 of the trunk line. This ground will be extended through spring 12 and bar 16 of the switch of the calling line, conductor 69, left-hand armature and contact spring 70 of relay 65 through the winding of relay 71 to grounded battery. Relay 71 is energized in this circuit and locked up over the same locking circuit which was traced for this relay when it was energized on account 75 of the busy condition of a calling line within the branch exchange. In attracting its outer left-hand armature, relay 71 completes a circuit from ground, outer left-hand armature and front contact of relay 71, springs 17, 18 and 41, springs 36 and 34 of stepping magnet 23, conductor 64, right-hand armature and front contact of relay 65, through the winding of relay 65, conductor 66, through the winding of stepping magnet 23 to grounded battery. Magnet 23 steps the bar 3 one step to the right so as to connect the springs of the next trunk line with the bars 15, 16, 17 and 18 of the calling line. In case this line is also busy, the previously 80 traced circuit for test relay 71 will be again completed and magnet 23 will be again energized. Thus magnet 23 will stop the bar 3 to the right until the springs of an idle trunk line engage the line bars of the calling line, at which time, no circuit being completed for test relay 71, this relay will retract its armatures to open the circuit for magnet 23. As relay 65 is included in this circuit, it will now be deenergized and a circuit 85 will be completed from ground, outer right-hand armature and front contact of relay 63, conductor 72, right-hand armature and back contact of relay 71, through the left-hand winding of relay 73, back contact and left-hand armature of relay 65, conductor 69, bar 16, spring 12, conductor 76, through the winding of relay 300 to grounded battery. Relays 73 and 300 are energized in this circuit, relay 73 in attracting 90 its outer left-hand armature completing a locking circuit for itself which may be traced from ground, outer right-hand armature and front contact of relay 63, conductor 72, outer left-hand armature and front contact of relay 73, through the right-hand winding of said relay to grounded battery, and in parallel with this circuit, extending around to the conductor 76 of the trunk line taken for use from the 95 inner-left hand armature and front contact of relay 73 and the circuit previously traced. Upon the energization of relays 300 and 73, a circuit is completed for cut-off relay 61 of the calling line which may be traced from grounded battery, through the winding of relay 61, springs 42 and 49, outermost right-hand armature and front contact of relay 73, and conductor 79, through the front contact and armature of relay 300 to ground. Relay 61 in attracting its armatures completes a circuit for line relay 301 of the trunk which may be traced from grounded battery, through the left-hand winding of relay 301, back contact and inner right-hand armature of relay 302, conductor 77, spring 43, bar 80 100 17, springs 40 and 46, front contact and outer armature of relay 61, through the apparatus at substation A, inner armature and front contact of relay 61, springs 44 and 39, bar 18, spring 14, conductor 78, outer right-hand armature and back contact of relay 302, through the right-hand winding of relay 301 to ground. Relay 301 in attracting its inner armature, completes an obvious circuit for relay 303 which is energized and completes a circuit from ground, front contact and armature of relay 303, conductor 75, spring 11, bar 15, through the winding of relay 63 to grounded battery. Relay 63 is held energized in this circuit during the remainder of the connection after relay 59 is deenergized due to the operation of relay 61. 105

In attracting its outer armature, relay 301 extends ground through the outer armature and spring 304 of relay 301 and the back contact and left-hand armature of relay 302, through the winding of supervisory relay 306 to the ring contact spring of jack 307. A circuit is also completed from ground, outer armature and spring 305 of relay 301, through the armature and contact of sleeve relay 308, and the winding of relay 309 to grounded battery. Relay 309 is energized in this circuit and, in attracting its armature, completes a circuit to light the line 110 lamp 310. 115

The operator, observing this light, inserts plug 311 of an idle cord circuit in answering jack 307, thereby completing a circuit from grounded battery, through the lower right-hand winding of repeating coil 312, through the winding of supervisory relay 313, ring contacts of plug 311 and jack 307, over the circuit traced for supervisory relay 306 to ground at the outer armature of relay 301. Relays 313 and 306 are energized in this circuit. Supervisory relay 313, in attracting its armature, provides a shunt circuit for lamp 314, extinguishing this lamp which was lighted over a circuit from battery, through lamp 314, sleeve contacts of plug 311 and jack 307, and sleeve relay 308 to ground upon the insertion of the plug in the jack. Relay 308, in attracting its armature, interrupted the circuit of relay 309 to 120 lamp 310. 125

extinguish lamp 310. Relay 306, in attracting its inner armature, completes an obvious circuit for relay 303 to hold this relay energized upon the deenergization of relay 301.

5 In attracting its outer armature, relay 306 completes an obvious circuit for relay 302. Relay 302 in attracting its right-hand armatures interrupts the circuit of relay 301 and completes a circuit from the central office 10 cord circuit to the calling substation which may be traced from ground, upper right-hand winding of repeating coil 312, tip contacts of plug 311 and jack 307, front contact and outer right-hand armature of relay 302, conductor 78, spring 14, bar 18, springs 39 and 44, front contact and inner armature of relay 61, through the apparatus at substation A, outer armature and front contact of relay 61, springs 46 and 40, bar 17, spring 20 13, conductor 77, inner right-hand armature and front contact of relay 302, through the winding of supervisory relay 306, ring contacts of jack 307 and plug 311, through the winding of supervisory relay 313 and the 25 lower right-hand winding of repeating coil 312 to battery. Relays 313 and 306 are held energized in this circuit and the operator, by depressing her listening key 315, will connect her head set, not shown, to the line and 30 may inquire the desired number and complete the connection to the called subscriber in any well-known manner. When the subscriber at station A replaces his receiver on its hook at the end of the conversation, he 35 interrupts the circuit traced for relays 313 and 306 to deenergize these relays. Relay 313, in deenergizing, removes the shunt around the lamp 314 to light this lamp and the operator thereupon removes the plug 40 311 from jack 307. Relay 306, in retracting its armatures, deenergizes relays 302 and 303. Relay 303, in retracting its armature, interrupts the circuit previously traced for relay 63 of the calling line and the consequent deenergization of this relay causes release of all the apparatus at the branch exchange in the manner described for the release of a connection between two substations within the branch exchange. Relay 73, 50 in deenergizing, interrupts the circuit for relay 300 and the system is completely restored.

The central office operator, desiring connection with a substation in the branch exchange shown in Fig. 1, after making the usual busy test with plug 200 and jack 201 on finding the line idle, inserts the plug 200 in the jack 201 and depresses her dialing key 202. In inserting the plug into the jack, a 55 circuit was completed from battery, through the winding of relay 203, sleeve contacts of plug 200 and jack 201, through a resistance, to ground, to energize relay 203. In depressing her dialing key, the operator completes 60 a circuit for line relay 59 of the trunk line which may be traced from grounded battery, through impedance 62, winding of relay 59, back contact and outer armature of relay 61, conductor 204, ring contacts of jack 201 and plug 200, lower alternate contact of dialing 70 key 202, through the normally closed springs of the operator's calling device 205, upper alternate contact of key 202, contact and armature of relay 203, tip contacts of plug 200 and jack 201, conductor 206, inner armature and back contact of relay 61, through impedance 60 springs 53 and 54 and secondary winding of tone source 80 to ground. Relay 59 is energized in this circuit, thereby 75 causing the energization of relay 63 in the same manner as was described for the case when a subscriber at the branch exchange initiated a call. The operator now dials the number of the wanted subscriber, thereby interrupting at the springs of the calling 80 device 205 the circuit traced for relay 59. After the operator has dialed this number, she releases her key 202, thereby completing a substitute circuit from the normal contacts of key 202 and the right-hand windings of 85 repeating coil 207 instead of through the alternate contacts of key 202 and the calling device 205 to maintain relay 59 energized. Since the operation of the switch at the branch exchange is exactly the same as was 90 described in connection with a call between branch exchange subscribers, it will not be further described at this time. In case the called line is busy, the operator by depressing her listening key 208 will receive a busy 95 tone and, after informing the calling subscriber, may remove the plug 200 from jack 201, thereby interrupting the circuit of relay 59 and causing the release of the apparatus at the branch exchange in a manner 100 previously described. In case the called line is idle, the operator will be informed of the termination of the conversation by the lighting of the supervisory lamp associated with the answering end of the cord circuit (not 105 shown) and will thereafter disconnect.

What is claimed is:

1. In a telephone system, an incoming line terminating in a set of multiple contacts, a number of outgoing lines, a contact operating member individual to each of said outgoing lines, a movable bar, means for imparting longitudinal motion to said bar, and mechanical means for successively actuating said contact operating members to interconnect said incoming line with said outgoing lines upon movement of said bar. 115
2. In a telephone system, an incoming line terminating in fixed bars, a movable bar parallel to said fixed bars, a number 120 of transverse arms resting on said movable bar, a number of outgoing lines terminating in contacts carried by said arms, and means controlled over said incoming line for advancing said movable bar to select 125
3. In a telephone system, an incoming line terminating in fixed bars, a movable bar parallel to said fixed bars, a number of transverse arms resting on said movable bar, a number of outgoing lines terminating in contacts carried by said arms, and means controlled over said incoming line for advancing said movable bar to select 130

- 6
- 5 tively operate said arms to interconnect said incoming line to one of said outgoing lines.
3. In an automatic switch, a number of 5 contact operating members, a movable bar, means for imparting longitudinal motion to said bar, and mechanical means for successively actuating said contact operating members upon movement of said bar.
- 10 4. In an automatic switch, a number of line bars, a number of arms, contacts carried on said arms to cooperate with said line bars; a movable bar to mechanically control the movement of said arms, and means 15 for moving said bar to selectively operate said contacts.
5. In an automatic switch, a number of pivoted arms, contacts individual to said arms operated by movement thereof, a 20 notched bar upon which said arms rest, and means for moving said bar to successively move said arms into engagement with said notches to operate their associated contacts.
6. In an automatic switch, a longitudinal- 25 ly movable bar, ratchet teeth on one surface of one bar, a number of pivoted arms resting on the opposite surface of said bar, a notch cut in said bar individual to each pivoted arm, the distance between successive notches being greater than the distance 30 between successive arms by an amount equal to the length of a number of said ratchet teeth, a pawl to cooperate with said ratchet teeth to move said bar to successively engage said arms with their notches, and contacts operated by the engagement of each arm with its notch.
7. In an automatic switch, a number of pivoted arms, a bar on which said arms rest, notches and a cam surface on said 40 bar to successively rotate said arms during the advancement of said bar, contacts individual to said arms operated by rotation thereof, and means for advancing said bar.

25 35 40 45
In witness whereof, I hereunto subscribe my name this 18th day of January A. D., 1920.

SAMUEL B. WILLIAMS, JR.
